AUTOMOBILE DOOR LOCK

Avagim Wartian, Detroit, Mich., assignor to The
Yale & Towne Manufacturing Company,
Stamford, Conn., a corporation of Connecticut

Application July 11, 1936, Serial No. 90,125

34 Claims. (CL 70—146)

This invention relates to a flush type of handle lock for use on automobile doors. In locks of this type, the outside handle for retracting the usual latch bolt is adapted to lie in a recess formed in the door panel and is maintained locked in that recess and under the control of locking means operated from the inside of the car and also from the outside of the car.

A basic feature of my invention embodies the retraction of the outside handle into its recess by operation of the inside handle, this retraction being accomplished through the bolt retracting means of the outside handle. More particularly, I provide an outside handle and means operated thereby for retracting the bolt, the operation of the bolt retracting means in a reverse direction by a handle on the inside of the door being effective to move the outside handle into its recess.

A further feature of the invention embodies means whereby the retraction of the latch bolt as by the slamming of the door acts to move the outside handle into its recess. This retraction of the outside handle may take place also when the bolt is retracted by the inside handle. It will be readily appreciated that automatic retraction of the handle into its recess when the door is slammed shut would be extremely dangerous, should the fingers of the operator be caught between the outside handle and the recess into which it is moved. Therefore, I form my outside handle operating means so that if the handle is moved more than a certain distance outside of its recess, which is naturally the case where the handle is being grasped by an operator, the handle operating means will become ineffective to move the handle into the recess.

As a further feature, I prefer to use a construction whereby the outside handle will in such a case be thrown even further away from its recess.

Still a further contribution of my invention is the particular construction of the outside handle and the means for locking the handle in its recess controlled from the outside of the lock. Preferably, these means constitute a push button which may be lock operated, and which is maintained in the handle proper.

A further feature of the invention embodies means whereby the outside handle may be locked in its recess by the inside handle, as well as by the outside locking means just described. By means of this construction, the inside handle may lock the outside handle against movement out of its recess, regardless of the operation of the outside button or cylinder. A bandit proof lock operation is thus obtained to prevent the opening

of the door whenever the car is occupied by one who does not wish to have the door opened.

A further feature of the invention is embodied in the construction of the outside handle and the bolt retracting mechanism operated thereby, whereby release of the outside handle when it is in its recess permits its movement out of the recess to a position from which it may readily be operated manually for retracting the latch bolt.

Still a further contribution of my invention is the construction of the escutcheon and handle, and their relation to one another, and the means for maintaining the handle and escutcheon in the recess so as to prevent unauthorized removal of the same from the outside. This contribution has been divided out of this application, and is covered in my application Serial No. 127,945, filed February 26, 1937.

There are, of course, additional features of the invention which are of extreme importance, such as the operation of the various parts of the lock and their construction, the release of the outside handle from the locking means operated by the inside handle when the door is slammed shut, etc. These features will of course be clearly described in the specification which follows, and will be claimed particularly in the claims appended hereto.

For a detailed description of my invention, I shall refer to the drawings in which Fig. 1 is a front view of the escutcheon and handle. Fig. 2 is a longitudinal section of Fig. 1, while Fig. 3 is a rear view of the parts of Fig. 1. Fig. 4 shows the operation of some of the parts of Fig. 2, while Fig. 5 is an end view of Fig. 2. Figs. 6 and 7 are end views of the cylinder lock used in my handle, while Fig. 8 shows a button used instead of a lock. Fig. 9 is a partial section and plan view of a door to which my lock is applied showing the outside handle just out of its recess. Fig. 10 is a view substantially along lines 10—10 of Fig. 9 illustrating the construction of the parts of Fig. 9. Fig. 11 is a view taken along lines 11—11 of Fig. 9. Fig. 12 is a view of some of the parts of Fig. 9 with the outside handle in bolt retracting position. Fig. 13 is a view of the lock of Fig. 10 showing the various parts when the bolt is retracted by the outside handle, as in Fig. 12. Fig. 14 is a view of the bolt retracting cam in the position which it occupies in Fig. 13, the cam being partially cut away in Fig. 13. Fig. 15 is a partial view along lines 15—15 of Fig. 12. Fig. 16 shows the relation of the parts when the latch bolt is retracted as by the slamming shut of the door. Fig. 17 shows

the position assumed by the outside handle when the door slams shut, as in Fig. 16. Fig. 18 shows the locking of the handle in its recess by operation of the remote control operated by the inside handle. Fig. 19 is a section substantially along lines 19-19 of Fig. 17. Fig. 20 illustrates the position of the parts when the outside handle is held out of its recess sufficiently to allow the fingers of the operator to lie between the handle and the recess. Fig. 21 illustrates the action of the parts of Fig. 20 when the latch bolt is retracted by the slamming shut of the door. Fig. 22 illustrates a modified form of retracting cam which acts in Figs. 20 and 21 to throw the outside handle away from its recess.

Referring now more particularly to the drawings, and especially to Figs. 1-7, 9 and 17, the handle assembly of my invention comprises an escutcheon plate 10 to which my handle 13 is pivoted on a pin 11 for movement into and out of a recess in the automobile door to which the lock is applied. The recess is shown diagrammatically and is designated by reference numeral 12 in Figs. 9 and 17. The handle 13 is shown formed separately from a retracting lug 14 for purposes of assembly, since the two parts may be made as one, as will be readily appreciated. In the preferred form, the retracting lug 14 is also pivoted on the pin 11.

The horizontal extending portion 15 of the handle is bored out to house a detent bolt 16 spring pressed outwardly by a spring 17 and retracted by a bell crank 18 actuated by a push button or a cylinder lock 19. On three handles of a four door sedan, a button 19 is used, while on the fourth handle, a cylinder lock is used, as will be appreciated by those skilled in the art.

A pin 20 limits the throw of the cylinder 19 when the cylinder is released for free movement. It is released for free movement when its locking cam 21 is moved by operation of the key plug 22 from the position of Figs. 2 and 6 to the position of Figs. 4 and 7. By this movement, the locking cam 21 is withdrawn from a slot 23 in the handle proper, and the endwise movement of the cylinder from the position of Fig. 2 to the position of Fig. 4 will, through the bell crank 18, retract the detent bolt 16. Naturally, this retraction of the detent bolt 16 will release the handle for movement from the position of Fig. 17 in the recess 12 to the position of Fig. 9 under the influence of a spring 24, provided the handle is not locked by additional and independent means to be described presently.

Both the handle 13 and the escutcheon plate 10 fit in the recess 12, the escutcheon plate being secured in the recess through a bayonet joint formed by its ear member 25 coacting with the edge 26 of one end of the recess 12. When the handle is locked in the recess through detent bolt 16, it is readily seen that outward movement of the escutcheon and handle from the recess 12 is impossible, the parts forming in effect a rigid bar held at one end by the detent bolt 16, and at the other end by the ear 25. Once the detent bolt 16 is retracted so that the handle may move to the position of Fig. 9, then of course the ear 25 may be moved endwise relatively to the end surface 26, thus removing the escutcheon and the handle from the recess. Screws housed in the holes 27 of the escutcheon 10 retain the escutcheon relatively to the door when the handle is in its position of Fig. 9, but the screws in the holes 27 have no retaining function when the handle

is in its locked position of Fig. 17. This construction is all covered in my divisional case supra.

The bolt of my door lock is designated by reference numeral 28, and has a main body carrying a pair of pins 29 and 30. These pins support a link 31 through a slot 32. The end surface of slot 32 impinging against the pin 29 will retract the latch bolt against the pressure of spring 40 when the remote control rod 33 is moved to the right in Fig. 10 by counterclockwise rotation of an inside handle 34. The handle 34 operates the rod 33 through means of a rotating crank 35 having an integral cam 36 which has depressions 37 and 38 cooperable with a detent spring 39.

I shall now refer to Figs. 9, 10, 12 and 13 to describe the means for retracting the bolt 28 by means of the outside handle 13. A U-shaped bolt retracting cam 41 is pivoted on the legs of its U at 42 and 43 to the U-shaped main frame plate 44 of the lock, and is adapted for rotary movement on said pivots 42 and 43 when actuated by the retracting lug 14 of the handle, this lug being cooperable with the surface 45 of the cam 41. Rotation of the cam 41 forces the up-turned lug 46 thereof to contact the surface 28a of the bolt and move the bolt from the position of Fig. 10 to the position of Fig. 13 by the movement of the outside handle 13 from the position of Fig. 9 to the position of Fig. 12.

When the bolt 28 is in its fully thrown position of Fig. 10, the retracting cam 41 is maintained in a balanced position by a relatively powerful spring 48 and with its up-turned lug 46 spaced from the bolt surface 28a. In this position of the parts, the retracting lug 14 of the outside handle 13 is in its dotted line position of Fig. 11, spaced from contact with the surface 45, if the handle is locked in its recess by bolt 16. If, in this position of the parts, the cylinder lock or push button 19 is depressed releasing the latch bolt 16, the handle is allowed to jump outwardly from the recess 12 under the influence of the spring 24 to its position of Fig. 9. The lug 14 then moves into its full line position of Fig. 11 against the surface 45. Manual swinging of the handle 13 from Fig. 9 to Fig. 12 now acts to retract the latch bolt through the retracting cam 41, the cam moving from its position of Fig. 10 to its position in Figs. 13 and 14. The relation of the retracting lug 14 to the surface 45 of the retracting cam 41 is well illustrated in Fig. 15. I have now explained just how the bolt 28 is retracted either by the outside handle 13 or the inside handle 34.

I shall now explain how the retracting movement of the latch bolt by the slamming shut of the door acts to move the outside handle 13 into its recess 12. This action is probably best shown in Fig. 16 wherein it will be readily seen that on the under side of the vertical extension of the body of bolt 28, there is a depending lug 47 which cooperates with the surface 28a of a heart shaped cut-away portion 49 of my retracting cam 41. The forceful retraction of the latch bolt 28 when it impinges against the strike 50 in Fig. 16, is such as to cause the lug 47 cooperating with the surface 48a to rotate the retracting cam 41 clockwise on its pivots 42 and 43 from the position of Fig. 10 to the position of Fig. 16. In so moving, the surface 45 of the retracting cam 41 will cooperate with the lug 14 of the handle 13 in a manner directly the reverse of its cooperation when the handle 13 acts to retract the latch bolt by swinging outwardly away from the recess 12.

The result of this action is to move the outside handle 13 into its recess, as illustrated in Fig. 17, which figure shows the positioning of the handle 13 when the parts of the lock are in their relation shown in Fig. 16. Naturally, when the outside handle moves into its position of Fig. 17, the latch bolt 16 locks the handle in its recess by coaction with the surface 16a of the recess, as will be readily appreciated.

10 While this movement of the outside handle into its recess is caused by the very forceful retracting of the bolt 28 incidental to its abutting a strike 50, substantially the same action may be obtained when the bolt is retracted by the inside handle 34, as previously described, if such action is desired. In my preferred construction, however, the bolt 28 is not retracted by the inside handle 34 in a manner to cause the lug 47 to rotate the cam 41 with the power required to 20 move the handle 13 into the recess.

In Figs. 20 and 21, I illustrate what happens when the bolt 28 is thrown back by a strike 50 at a time when handle 13 is sufficiently out of its recess 12 to permit the insertion of fingers between it and its recess. It will readily be appreciated that when the handle 13 is out of its recess in the position shown in Fig. 9, the cam 41 is in its position of Fig. 10 and is maintained balanced by the spring 48 with surface 48a opposite depending lug 47. If, however, the handle 13 is rotated somewhat in a clockwise direction in Fig. 9, it will rotate the cam 41 counterclockwise about pivot point 43 in Fig. 10, thus bringing the point 51 of the heart shaped cut-away portion 49 just above the end of the lug 47, as shown in Fig. 20. Retraction of the bolt 28 by a strike, as in Fig. 21, will now cause the lug 47 to abut the surface 52 of the cut-away heart portion 49, rather than the surface 48a, as in the action 40 shown in Fig. 16.

Thus, the forceful retraction of the latch bolt 28 incidental to its abutting a strike 50 will cause the lug 47 to cooperate with the surface 52 rotating the cam 41 counterclockwise, and therefore 45 away from the retracting lug 14 of handle 13. In the modification of Fig. 22, a circular surface 45a is shown on the cam 41, formed as an extension of the surface 45, and has a double coaction with the lug 14. If the bolt 28 is retracted 50 by the slamming shut of the door, with the fingers of the operator between the handle and the recess 12 as described above, should the cam modification of Fig. 22 be used, the handle 13 will actually be thrown away from the recess 12. This 55 insures the safety of the operator's fingers.

I shall now refer to the remote control means actuated by the inside handle 34, and which are operable to move the outside handle into its recess and to lock the same in its recess independently of the outer locking means embodied in the latch bolt 16 and the controlling cylinder 19. The link 31 used for retracting the latch bolt by the counterclockwise rotation of the handle 34 from its position in Fig. 10, has an extension 60 cooperable with a pin 61 formed on the retracting cam 41 for rotating the retracting cam in a clockwise direction on its pivots 42 and 43, or from its position of Fig. 10 to its position of Fig. 18. When this is done, as is shown in Fig. 18, the handle 13 is moved into the recess 12 through the coaction of the lug 14 of the handle 13 with the surface 45 of the cam 41, as is best illustrated in Figs. 17 and 19.

Because the cam 41 is locked in its position of Fig. 18 by the extension portion 60 cooperating

with the pin 61, the handle 13 is maintained locked in the recess 12 regardless of the release of the latch bolt 16 by the cylinder or push button 19, as the case may be. In this way, anyone in the car may readily lock the car against access from anyone having the key, in the case of the locking door, or from anyone operating the push button 19 in the case of the doors not equipped with a key lock.

10 In order to prevent the locking out of the owner of the car should he open the door and leave the parts of the lock in the position of Fig. 18, and then slam the door shut, I provide a throw-out of the outside handle locking means. This throw-out is operated by the pin 30 carried 15 by the bolt 28 and cooperable with the right hand end of the slot 32 of the link 31. If the bolt 28 impinges against the strike and is moved to the right from its position of Fig. 18, it is quite obvious that the pin 30 will move the link 31 to 20 the right and will therefore release the pin 61, allowing the cam 41 to be rotated in a counterclockwise direction on pivots 42 and 43 under the influence of its spring 48. This, of course, moves the cam and its portion 45 to the position of Fig. 25 11 with the lug 14 of the handle 13 in its dotted line position, so that the handle 13 may thereafter be readily released by retraction of the latch bolt 16 in a manner illustrated in Fig. 9.

While I have now fully described the various 30 operations of my lock, I should like to go through a complete cycle of those operations in order to better explain the relation of the parts which have been described in detail.

In Fig. 10, the lock is shown with the inside 35 handle 34 in a neutral position and with the latch bolt 28 fully thrown. In this position of the parts, the outside handle 13 may occupy a locked position within the recess 12, as illustrated in Fig. 17, and if so, its lug 14 will be in the dotted line 40 position of Fig. 11 relatively to the portion 45 of the retracting cam 41. If now the push button or lock 19, as the case may be, is depressed from the position of Fig. 2 to the position of Fig. 4, the detent bolt 16 is retracted and the handle 13 may 45 move to the release position of Fig. 9.

From this position of Fig. 9, it may be rotated to the position of Fig. 12, thus moving the cam 41 to its position of Fig. 14 and retracting the bolt 28, as is illustrated in Fig. 13, this movement having no effect whatsoever on the inside handle 34.

If, with the parts of the lock in the position of Fig. 10, the door is locked, and the outside handle 13 is outside of its recess as in Fig. 9, the inside handle 34 may pull in the outside handle and 55 lock it in its recess. To do this, the inside handle is rotated clockwise from its position of Fig. 10 to its position of Fig. 18, extension 60 of link 31 cooperating with pin 61 of the cam 41 to rotate the cam so as to cause the handle surface 45 to 60 abut lug 14 of the outside handle 13 to move the outside handle into its recess 12. This operation will also lock the outside handle in its recess 12 because of the relation of the retracting lug 14 with the surface 45 of the retracting cam 41, and 65 this locking of the handle in the recess 12 will be effective, regardless of the retraction of the detent bolt 16 by the cylinder 19. Naturally, a reverse rotation of the handle 34 to its position of Fig. 10 will leave the outside handle in its recess 70 but will release it for outward movement under the control of the cylinder 19. Movement of the inside handle 34 is somewhat controlled by the coaction of the spring 39 with the depressions 75 37 and 38 of the link 35, as will be understood.

With the parts of the lock in the position of Figs. 9 and 10 and the door open, should the door be slammed shut, the coaction of the bolt 28 with a strike 50 will retract the bolt, as is illustrated in Fig. 16. This will cause the lug 47 on the under side of the vertical extension of the bolt 28 to rotate the cam 41 clockwise through its coaction with the surface 48 of the heart shaped cut-out portion 49 of the cam 41. This clockwise rotation illustrated in Fig. 16 will naturally cause the movement of the outside handle 13 into its recess in the same way that the handle is moved into its recess by the clockwise rotation of the cam 41 in Fig. 18. The handle will not, however, be locked in its recess except by the detent bolt 16 and may thereafter be readily released by the pushing in of the cylinder 19.

If the outside handle 13 is positioned slightly beyond its position of Fig. 9 out of the recess 12, as by the placing of the fingers of the operator between the handle and the recess 12, the slamming shut of the door will not move the handle into its recess, as just described. When the outside handle 13 is moved away from its recess by the positioning of the operator's fingers between it and the recess, the cam 41 is moved to its position of Fig. 20, thus bringing the under surface 52 of the cam 41 opposite the depending lug 47. If now the door be slammed shut, the retracting movement of the latch bolt 28 will cause the depending lug 47 to rotate the cam 41 counter-clockwise by coaction with the surface 52, and this will throw the outside handle further away from the recess, if the cam construction shown in Fig. 22 is utilized. If, on the other hand, the construction shown in Fig. 14 is utilized, the outside handle will simply remain in the particular position in which it is being held.

I now claim:

40 1. A door lock including an outside handle mounted for movement into and out of a recess in the outer side of a door to which said lock is applied, a latch bolt, means whereby said latch bolt is retracted by movement of said handle, and means whereby a retractive movement of the latch bolt independently of said handle moves said handle into its recess.

50 2. A door lock including an outside handle mounted for movement into and out of a recess in the outer side of a door to which said lock is applied, a latch bolt, means whereby said latch bolt is retracted by swinging of said handle away from said recess, and means operable by said latch bolt as it is retracted other than by said handle for swinging said handle into said recess.

60 3. A door lock including an outside handle mounted for movement into and out of a recess in the outer side of a door to which said lock is applied, means for locking said handle in said recess when said handle is moved into said recess, a latch bolt, means actuated by swinging movement of said handle away from said recess from a position outside of said recess for retracting said latch bolt, and means whereby retractive movement of said latch bolt by other than said handle swings said handle from said outside position into said recess.

70 4. A door lock including an outside handle mounted for movement into and out of a recess in the outer side of a door to which said lock is applied, means for locking said handle in said recess when said handle is moved into said recess, a latch bolt, cam means connected to said handle whereby swinging movement of said handle away from said recess from a position out-

side of said recess retracts said latch bolt, and means whereby retraction of said latch bolt as by the slamming of the door actuates said cam means to swing said handle from said outside position into said recess.

5 5. A door lock including an outside handle mounted for movement into and out of a recess in the outer side of a door to which said lock is applied, a latch bolt, means whereby said latch bolt is retracted by movement of said handle, a spring biased to project said handle out of its recess, and means whereby a latching back of the latch bolt independently of said handle moves said handle into its recess against the pressure of said spring.

10 6. A door lock including an outside handle mounted for movement into and out of a recess in the outer side of a door to which said lock is applied, means for locking said handle in said recess when said handle is moved into said recess, a latch bolt, cam means actuated by said handle whereby swinging movement of said handle away from said recess from a position outside of said recess retracts said latch bolt, a spring biased to project said handle out of its recess, and means whereby retraction of said latch bolt as by the slamming of the door actuates said cam means to swing said handle from said outside position into said recess against the pressure of said spring.

15 7. A door lock including an outside handle mounted for movement into and out of a recess in the outer side of a door to which said lock is applied, a latch bolt, means whereby said latch bolt is retracted by movement of said handle, a cam member connected to said handle for moving said handle into its recess, said cam member being movable in turn by said handle as said handle is manually actuated, means for moving said cam member when said latch bolt is retracted as by the slamming shut of the door, and a portion of said cam member, if particularly positioned by said outside handle, actuated by said retracting latch bolt to move said outside handle into its recess.

20 8. A door lock including an outside handle mounted for movement into and out of a recess in the outer side of a door to which said lock is applied, a latch bolt, means whereby said handle retracts said latch bolt as it moves relatively to said recess, a part of said handle formed as a horizontally extending portion, a spring pressed detent bolt in said portion cooperable with means defining said recess for locking said handle in said recess, and a push button on said handle for retracting said detent bolt.

25 9. A door lock including an outside handle mounted for movement into and out of a recess in the outer side of a door to which said lock is applied, means for locking said handle in said recess and releasing said handle from said recess operable from the outside of said door, means for moving said handle into said recess and for locking said handle in said recess operable from the inside of said door and maintained out of control of said outside locking and releasing means, said outside handle locking means being rendered effective to lock said handle in said recess when said handle is moved into said recess by said means operable from the inside.

30 10. A door lock including an outside handle mounted for movement into and out of a recess in the outer side of a door to which said lock is applied, an inside handle, a bolt retracting cam adapted to lie in a neutral position, means of con-

nection between said outside handle and said cam whereby a particular operation of said outside handle moves said bolt retracting cam in a bolt retracting direction independently of said inside handle, means whereby said inside handle moves said cam opposite to said bolt retracting direction, said cam when so moved being operative through said means of connection to move said outside handle into its recess.

10 11. A door lock including an outside handle mounted for movement into and out of a recess in the outer side of a door to which said lock is applied, a bolt retracting cam, means of connection between said outside handle and said cam whereby a particular operation of said outside handle moves said bolt retracting cam in a bolt retracting direction, an inside handle, means whereby said inside handle moves said cam opposite to said bolt retracting direction, said cam when so moved being operative through said means of connection to move said outside handle into its recess and to lock said outside handle in said recess.

15 12. A door lock including an outside handle mounted for movement into and out of a recess in the outer side of a door to which said lock is applied, a bolt retracting cam, a bolt retractable by said cam, means of connection between said outside handle and said cam whereby a particular 20 operation of said outside handle moves said bolt retracting cam in a bolt retracting direction, an inside handle, means whereby said inside handle moves said cam opposite to said bolt retracting direction, said cam when so moved being operative through said means of connection to move said outside handle into its recess, means whereby said cam when so moved locks said outside handle in said recess, and means operable by the retraction of said bolt incidental to the slamming of the door adapted to release said outside handle from said locking means.

25 13. A door lock including an outside handle mounted for movement into and out of a recess in the outer side of a door to which said lock is applied, a bolt, means of connection between said outside handle and said bolt whereby a particular 30 operation of said outside handle retracts said bolt, an inside handle, means whereby operation of said inside handle moves said outside handle into said recess and locks said outside handle in said recess, and means operable by the retraction of said bolt incidental to the slamming of the door adapted to release said outside handle from its inside handle locking means.

35 14. A door lock including an outside handle mounted for movement into and out of a recess in the outer side of a door to which said lock is applied, a bolt retracting cam, a bolt retractable by said cam, means of connection between said outside handle and said cam whereby a particular operation of said outside handle moves said bolt retracting cam in a bolt retracting direction, an inside handle, means whereby said 40 inside handle moves said cam opposite to said bolt retracting direction, said cam when so moved being operative through said means of connection to move said outside handle into its recess and to lock said outside handle in said recess, outside locking means operable from the outside of said door for locking said outside handle in its recess once it is moved into said recess, and means operable by the retraction of said bolt incidental to the slamming of the door adapted to release 45 said outside handle from its inside handle lock-

ing means while not affecting said outside locking means.

15 16. A door lock including an outside handle mounted for movement into and out of a recess in the outer side of a door to which said lock is applied, a bolt retracted by swinging movement of said outside handle, an inside handle, means whereby said inside handle moves said outside handle into its recess and locks it in said recess, additional locking means for locking said handle in said recess rendered effective when said outside handle is moved into its recess by said inside handle, and means whereby the retraction of said bolt, as by the slamming of the door into shut position, releases said outside handle from said inside handle locking means while leaving said handle locked by said additional locking means.

20 17. A door lock including an outside handle mounted for movement into and out of a recess in the outer side of a door to which said lock is applied, a bolt retracted by movement of said outside handle, an inside handle, means whereby said inside handle moves said outside handle into its recess and locks it in said recess, and means 25 whereby the retraction of said bolt, as by the slamming of the door into shut position, releases said outside handle from said inside handle locking means.

25 18. A door lock including an outside handle mounted for movement into and out of a recess in the outer side of a door to which said lock is applied, a bolt retracting cam, a retractor lug mounted on said handle for operating said cam, a lazy connection between said retracting cam 30 and said lug whereby said handle may move a predetermined distance out of said recess without exerting retracting pressure on said cam, a spring pressing said handle out of said recess and tending to move said handle said predetermined distance, and means whereby the retraction of the latch bolt as by the slamming of the door acts through said cam and lug to move said outside handle into said recess.

35 19. A door lock including an outside handle mounted for movement into and out of a recess in the outer side of a door to which said lock is applied, a bolt retracting cam, a retractor lug mounted on said handle for operating said cam in a bolt retracting direction, a lazy connection 40 between said retracting cam and said lug whereby said handle may move a predetermined distance out of said recess without exerting retracting pressure on said cam, an inside handle, and means whereby rotation of said inside handle 45 rotates said cam in a direction opposite to its bolt retracting direction, movement of said cam by said inside handle being adapted through said lug to move said outside handle into its recess.

45 20. A door lock including an outside handle mounted for movement into and out of a recess in the outer side of a door to which said lock is applied, a latch bolt, a spring biased to project said handle out of its recess, means operated by said latch bolt as it is retracted by the closing 50 of the door for moving said handle into said recess against the pressure of said spring, an inside handle, said latch bolt operated means being operable also by said inside handle for moving said outside handle into its recess.

55 21. A door lock including an outside handle mounted for movement into and out of a recess in the outer side of a door to which said lock is applied, a latch bolt, an inside handle, a cam operated by said outside handle to retract said 60

- latch bolt, means whereby retraction of the latch bolt as by the slamming of the door so moves said cam as to force said outside handle into its recess, and means operated by said inside handle for also so moving said cam as to force said outside handle into its recess.
21. A door lock including an outside handle mounted for movement into and out of a recess in the outer side of a door to which said lock is applied, a latch bolt, means whereby said latch bolt is retracted by movement of said handle, and means including said first means operated by the retractive movement of the latch bolt as when the door is slammed shut for moving the handle into said recess.
22. A door lock including an outside handle mounted for movement into and out of a recess in the outer side of a door to which said lock is applied, a latch bolt, means whereby said latch bolt is retracted by swinging of said handle away from said recess, means movable by retractive movement of the latch bolt and adapted to contact a cam movable by said outside handle whereby to swing said outside handle into its recess when said latch bolt is retracted other than by said outside handle, said cam being movable by swinging movement of said outside handle to a position wherein said cam is not actuated by said retractive movement of the latch bolt to move said outside handle into its recess.
23. A door lock including an outside handle mounted for movement into and out of a recess in the outer side of the door to which said lock is applied, a bolt, a bolt retracting cam, an inside handle, means of connection between said outside handle and cam whereby when said outside handle moves outwardly of said recess it moves said cam to retract said bolt independently of said inside handle, means whereby said inside handle moves said bolt retracting cam, said cam when moved by said inside handle operating through said means of connection with said outside handle to move said outside handle into its recess.
24. A door lock including an outside handle mounted for movement into and out of a recess in the outer side of a door to which said lock is applied, a cam mounted for rotation, an inside handle and means whereby it rotates said cam in one direction from a neutral point, a latch bolt retracted by rotation of said cam by said outside handle, latch bolt retracting means independent of said cam and operated by said inside handle, and means whereby when said cam is rotated opposite said one direction by said inside handle it moves said outside handle into its recess.
25. A door lock including an outside handle mounted for movement into and out of a recess in the outer side of a door to which said lock is applied, a cam mounted for rotation in opposite directions from a neutral position, an inside handle and means whereby it rotates said cam in one direction from said neutral position, a latch bolt retracted by rotation of said cam by said outside handle, latch bolt retracting means independent of said cam and operated by said inside handle, means whereby when said cam is rotated by said inside handle in said one direction from said neutral position it moves said outside handle into its recess, said last named means retaining said cam and inside handle in the position to which they are rotated whereby to lock said outside handle in its recess, and means whereby the retraction of the bolt incl-
- dental to the slamming shut of the door moves said inside handle and cam to release said outside handle.
26. A door lock including an outside handle mounted for movement into and out of a recess in the outer side of the door to which said lock is applied, a latch bolt, an inside handle movable in an arc from one extreme position to another extreme position, means of connection whereby when said inside handle is moved to one of its extreme positions it first moves said outside handle into its recess, and thereafter through said means maintains said outside handle locked in said recess so long as the inside handle remains in said extreme position, said means of connection being of a one-way type so as to allow return of said inside handle to a central position while said outside handle remains in said recess, and means whereby movement of said inside handle to its other extreme position retracts said latch bolt.
27. A door lock including an outside handle mounted for movement into and out of a recess in the outer side of a door to which said lock is applied, an inside handle, a bolt retracting cam, means of connection between said outside handle and said cam whereby a particular operation of said outside handle moves said bolt retracting cam in a bolt retracting direction independently of said inside handle, means whereby said inside handle moves said cam opposite to said bolt retracting direction, said cam when so moved being operative through said means of connection to move said outside handle into its recess.
28. A door lock including an outside handle mounted for movement into and out of a recess in the outer side of a door to which said lock is applied, a latch bolt, and means whereby a retractive movement of the latch bolt as by the slamming of the door moves said handle into its recess.
29. A door lock including an outside handle mounted for movement into and out of a recess in the outer side of a door to which said lock is applied, a latch bolt and means whereby it is retracted by movement of said handle, and means whereby a retractive movement of the latch bolt independently of said handle moves said handle into its recess.
30. A door lock including an outside handle mounted for movement into and out of a recess in the outer side of a door to which said lock is applied, a latch bolt, means operated by the retractive movement of the latch bolt as when the door is slammed shut for moving the outside handle into said recess, said outside handle when moved partly out of said recess moving said means to a position in which retractive movement of the bolt will be ineffective to operate said means to move the outside handle into its recess.
31. A door lock including an outside handle mounted for movement into and out of a recess in the outer side of a door to which said lock is applied, a latch bolt, means operated by the retractive movement of the latch bolt as when the door is slammed shut for moving said handle into said recess, and means whereby when said outside handle is in a predetermined zone outside said recess said means operated by the retractive latch bolt will be functionally dissociated from said outside handle.
32. A door lock including an outside handle mounted for movement into and out of a recess in the outer side of a door to which said lock

is applied, a latch bolt, means whereby a latch-
ing back of the latch bolt independently of said
handle moves said handle into its recess, said
means having a part thereof movable by said
5 outside handle, the positioning of said part in a
particular zone corresponding to a particular po-
sition of said outside handle, being a prerequisite
to movement of said outside handle into its recess
by said means.

10 33. A door lock including an outside handle
mounted for movement into and out of a recess
in the outer side of a door to which said lock is
applied, a bolt retracting cam movable with said
handle to retract said latch bolt, an inside han-
dle, means whereby said inside handle moves said
15 cam and therefore said outside handle into said

recess, and means for dogging said cam when so
moved by the inside handle whereby to lock said
outside handle in said recess.

34. A door lock including an outside handle
5 mounted for movement into and out of a recess
in the outer side of a door to which said lock is
applied, a bolt retracting cam movable with said
handle to retract said latch bolt, an inside han-
dle, means whereby said inside handle moves said
10 cam and therefore said outside handle into said
recess, means for dogging said cam when so
moved by the inside handle whereby to lock said
outside handle in said recess, and means whereby
the retraction of the bolt as by slamming of the
door releases said cam from said dogging means. 15
